RAILWAY CAR WALL

William J. Tangerman, Hammond, Ind., assignor
to Union Metal Products Company, Chicago,
Ill., a corporation of Delaware

Application March 13, 1935, Serial No. 10,866

3 Claims. (Cl. 105—409)

The invention relates to railway freight cars and more particularly to side and end walls for open top railway cars, such as hopper and gondola cars, though the construction is adaptable 5 for walls of house cars, such as box, automobile and refrigerator cars. The construction is also adaptable for use as roofs, floors, hopper doors and side doors for railway cars. A roof or a 10 floor comes within the meaning of the term "wall" as used in the specification and claims herein.

Railway freight cars are generally designed so that the side walls are girders or trusses to carry part of the weight of the lading and the car 15 itself to the body bolsters which transmit such load to the trucks. Such side walls also retain the load in the car. It is desirable to make the inside horizontal width of the car as wide as possible to increase the cubical capacity of the 20 car but the outside width of the car is limited by tunnels and projections adjacent the track so it becomes imperative to make the side wall as thin horizontally as possible consistent with strength requirements.

25 Open top railway cars are frequently built with the vertical walls comprising spaced apart upper and lower frame members connected at spaced intervals by vertical posts with panels filling the spaces between the posts and frame members, 30 which construction forms a girder and retaining wall. It has been proposed to bulge the central parts of these panels outwardly to increase the cubical capacity of the car, such as shown in the Hart Patent No. 1,623,591 of April 5, 1927.

35 One of the objects of my invention is to provide a wall panel for a railway car which provides the maximum inside width of the car consistent with given outside width limitations, which panel is easily made, easily assembled 40 upon the car and which is very light in weight for its strength, and another object is to assemble a plurality of such panels in a railway car so that the marginal portions of adjacent panels are formed and secured together to provide vertical 45 posts between the upper and lower chords of the girder, which posts have adequate strength and yet occupy very little of the loading compartment of the car, thus helping to further increase the cubical capacity of the car.

50 Another object is to provide a panel having the central part offset from the marginal parts with integral stiffeners along opposite sides for various uses in a railway car.

Another object is to provide a panel of novel 55 construction wherein the body or main portion

of the panel is offset relative to the marginal portions for certain advantages pertinent to the particular article for which the panel is used and wherein certain sides of the panel comprise stiffening means which strengthen the offset body 5 portion, form means of attachment of the panel to other parts of the car or to similar panels when associated therewith.

Another object of the invention is to provide wall sheets for a railway car wall wherein the 10 posts or stakes are formed integral with the body of the sheet, thereby reducing the number of parts to be made, assembled and secured together. By welding the adjacent wall sheets together the adjacent walls of adjacent corruga- 15 tions may be placed very close together, thereby reducing the amount of cubic feet occupied by the stake so that the stake reduces the cubical lading capacity of the car to minimum amount.

Another object of the invention is to shape the 20 wall sheets so that they may be formed between reciprocating dies by bending instead of stretching the metal.

In the drawings:

Fig. 1 shows a partial elevation of a railway 25 car incorporating my improvement.

Fig. 2 is a section on line 2—2 of Fig. 1.

Fig. 3 is a section on line 3—3 of Fig. 1.

Fig. 4 is a section on line 4—4 of Fig. 1 with the upper chord omitted.

Fig. 5 is a perspective view of the side wall of a car according to my invention.

30 My improved wall comprises an upper chord 2 and lower chord 3, or frame members, in combination with a plurality of wall sheets 4 extending between and secured to the chords, respectively, and to each other.

35 Each wall sheet comprises side marginal parts 7, end marginal parts 8 preferably in substantially the same plane as the side marginal parts, 40 spaced apart parallel corrugations 9 extending preferably between opposite edges of the sheet, a central portion 12 extending between said corrugations 9 in a spaced apart plane from the marginal parts and below the plane of the tops 45 13 of the corrugations 9 and connecting portions 15—16 between the central portion 12 and the end marginal parts, respectively.

The adjacent side marginal parts 7 of adjacent sheets are secured together preferably by 50 welding 19 (or may be overlapped and riveted) so that the two adjacent side marginal parts 7—7 and the two adjacent corrugations 9—9 (Fig. 3) combine to form a very strong post or column between the upper (2) and lower (3) chords and 55

also combine to form a very strong beam between these chords 2—3 to resist horizontal thrust of a plastic lading. The end marginal parts 8 of the wall sheets are secured to the upper and lower chords, respectively, by welding 21, as shown in Fig. 5, or by overlapping the riveting, as shown in Fig. 2.

The central portion 12 of each sheet is positioned below the plane of the top 13 of the corrugations 9 to form a bead 24 for stiffening purposes and so as to protect the lettering on the car which may be stenciled on the central portions 12 of the several plates.

The outer parts of tops 13 of the corrugations 9 are preferably positioned flush with the outer edges 25 of the chords and the central portions 12 of the wall sheets are positioned as near thereto as possible and still obtain the advantages enumerated herein whereby the cubical capacity of the car is decreased the minimum amount.

In the wall sheet described the parts are so proportioned and arranged that the length of the center line of the metal of any horizontal cross section from side to side of the wall sheet is the same as any other cross section parallel thereto so that the plate while being formed between reciprocating dies is bent and not stretched. Thus in my design of wall sheets relatively thin plates may be pressed cold and relatively thick plates may be pressed with very little heat. Local stretching of a metallic sheet while being formed reduces its resistance to corrosion by disrupting the metal.

The lower connecting portion 15 merges into the end marginal part 8 above the top of the lower chord 3 so that lading will be discharged freely and also the upper marginal part 16 merges into the end marginal part 8 below the bottom of the upper chord 2 so that the lading will be freely discharged when the car is turned upside down in an unloading machine. (The drawings show a hopper car having hopper sheets 28—29).

Fillers 30 are used for closing the ends of the corrugations 9 above the top of the lower chord 3 and other fillers 31 are used for closing the ends of the corrugations 9 below the bottom of the upper chord 2. The interior surfaces of these fillers 30 and other fillers 31 are preferably flush with the interior surface of the adjacent connecting portions 15 and 16 to avoid pockets which would retain part of the lading in the car and cause corrosion.

The accompanying drawings illustrate the preferred form of the invention, though it is to be understood that the invention is not limited to the exact details of construction shown and described, as it is obvious that various modifications thereof,

within the scope of the claims, will occur to persons skilled in the art.

I claim:

1. A wall for a railway car comprising an upper chord, a lower chord and a plurality of wall sheets; each sheet comprising side marginal parts secured to the side marginal parts of adjacent wall sheets, end marginal parts secured to said chords, respectively, spaced apart corrugations extending between and overlapping said chords, respectively, a central portion in a spaced apart plane from the side marginal parts below the plane of the tops of said corrugations and connecting portions between said central portion and said end portions, said connecting portions merging into said end marginal parts above the top of the lower chord and below the bottom of the upper chord.

2. A wall for a railway car comprising an upper chord, a lower chord and a plurality of wall sheets; each sheet comprising side marginal parts secured to the side marginal parts of adjacent wall sheets, end marginal parts secured to said chords, respectively, spaced apart corrugations extending between and overlapping said chords, respectively, a central portion in a spaced apart plane from the side marginal parts below the plane of the tops of said corrugations and connecting portions between said central portion and said end portions, said connecting portions merging into said end marginal parts above the top of the lower chord and below the bottom of the upper chord.

3. A wall for a railway car comprising an upper chord, a lower chord and a plurality of wall sheets; each sheet comprising side marginal parts secured to the side marginal parts of adjacent wall sheets, end marginal parts secured to said chords, respectively, spaced apart corrugations extending between and overlapping said chords, respectively, a central portion in a spaced apart plane from the side marginal parts below the plane of the tops of said corrugations and connecting portions between said central portion and said end portions, said connecting portions merging into said end marginal parts above the top of the lower chord and below the bottom of the upper chord, and fillers closing the ends of said corrugations above the top of the lower chord and other fillers closing the upper ends of said corrugations below the bottom of the upper chord.

WILLIAM J. TANGERMAN.
